UNITED STATES PATENT OFFICE.

NAPOLEON TEBO AND THEODORE B. FRENCH, OF GRAFTON,
MASSACHUSETTS.

CARRIAGE-AXLE NUT.

SPECIFICATION forming part of Letters Patent No. 718,171, dated January 13, 1903.

Application filed September 5, 1901. Serial No. 74,439. (No model.)

To all whom it may concern:

Be it known that we, NAPOLEON TEBO and THEODORE B. FRENCH, citizens of the United States, residing at Grafton, in the county of 5 Worcester and State of Massachusetts, have invented a new and useful Carriage-Axle Nut, of which the following is a specification.

This invention relates to an attachment for carriage-axles which is designed to provide 10 means for tightening the washers employed at the end of wheel-hubs.

The especial object of this invention is to provide a simple, efficient, strong, and inexpensive attachment for carriage-axles, which 15 can be applied to carriage-axles which are already in use and which will afford means for tightening the washers, and which will have a wide range of adjustment, so that comparatively thin washers may be employed, even 20 when the wheel-hub is shortened or worn down to a considerable extent.

To these ends this invention consists of the axle attachment and of the combinations of an axle therewith, as hereinafter described, 25 and more particularly pointed out in the claim at the end of this specification.

In the accompanying drawings, Figure 1 is a sectional view of a wheel-hub, showing an 30 attachment constructed according to this invention applied to the axle thereof. Fig. 2 is a perspective view of the bushing which is threaded onto the end of the axle. Fig. 3 is a perspective view of the lock-nut for holding the parts in their adjusted position. Fig. 4 is a perspective view of the washer-retaining 35 nut, and Fig. 5 is a perspective view of the leather washer.

In ordinary carriage-wheel construction the wheel is usually held in place by a single nut, 40 which is threaded onto the end of the axle with a right-hand or left-hand screw-thread, as the case may be, and which is screwed up tightly against the shoulder of the axle. To prevent end play of the wheel, leather washers 45 are usually employed both on the inner and outer sides of the hub. In actual practice these washers have to be frequently renewed, and washers of exactly the right thickness have to be employed in order to keep a carriage-wheel in good running condition. When 50 the washer at the inner side of the nut is

worn comparatively thin or when the ends of the wheel-hub itself are worn out to a considerable extent, it frequently happens that a washer of undesirable thickness or two or 55 more washers have to be employed on the outer side of the wheel. The use of thick leather washers or of two or more washers together is objectionable because of not providing a firm end bearing for the wheel and 60 on account of the liability to shrink or swell, according to the amount of oil which is used on the axle.

The especial object of the present invention is therefore to provide an attachment for 65 carriage-axles which will permit of an adjustment, so as to avoid rewashering the wheel at the frequent intervals now required, and which will permit the use of comparatively 70 thin washers even when the ends of the wheel-hub are more or less worn.

Referring to the accompanying drawings and in detail, as shown in Fig. 1, A designates an ordinary wheel-hub, which is provided with a metal bushing B. Extending 75 through the hub is an ordinary carriage-axle C, having collars for holding the inner washer E in place and for forming a groove for retaining oil. At its outer end the axle C is provided with a threaded section F, and these 80 parts may be of ordinary or approved construction and need not be herein described at length.

An attachment for an ordinary carriage-axle constructed according to this invention 85 comprises a bushing 10, which is threaded onto the end of the axle C. As illustrated most clearly in Fig. 2, the bushing 10 is provided with a wrench-section 11 and with oppositely-threaded sections 12 and 13. 90

As shown most clearly in Fig. 1, the outside diameter of the bushing 10 is preferably slightly larger than the diameter of the axle C. Threaded onto the bushing 10 is the main nut 14, having a pocket on its inner face for 95 receiving a comparatively thin leather washer 15. In this construction it will be noted that the inside diameter of the main nut 14 is slightly larger than the body portion of the axle C. We regard this as an especially important feature of our construction, because this permits the main nut 14 to be screwed 100

back over the end of the body portion of the axle, allowing a tightening up of the wheel even when the barrel portion of the hub has been worn at its ends, so as to render the 5 same considerably shorter than the body-portion section of the axle. Threaded onto the section 12 of the bushing 10 is a lock-nut 16 for holding the main nut 14 in its adjusted position.

10 As shown most clearly in Figs. 3 and 4, the body portions of the nuts 14 and 16 are preferably hexagonal, so that they may be turned by an ordinary carriage-wrench, and the engaging faces of said nuts are preferably 15 knurled or provided with ridges for locking the ends more firmly together when tightened together. By means of this construction it will be seen that we have provided a simple and efficient construction for tightening a 20 carriage-wheel without the necessity of re-washing the same, and as the main nut 14 can be threaded back over the body portion of the axle C we have provided a construction by means of which narrow hubs or hubs the 25 ends of which are more or less worn may be used in connection with comparatively thin washers.

We are aware that changes may be made in practicing the invention by those who are

skilled in the art without departing from the 30 scope thereof as expressed in the claims. We do not wish, therefore, to be limited to the construction we have herein shown and described; but

What we do claim, and desire to secure by 35 Letters Patent of the United States, is—

In a construction of the class described, the combination of an axle, a bushing having interior screw-threads fitting onto the threaded end of the axle and having oppositely-inclined 40 exteriorly-threaded sections 12 and 13 having a reduced wrench-section 11, a stop-nut 16 which can be applied or removed over the wrench-section 11, and a main nut 14 holding a leather washer in place and having an 45 inside diameter greater than the diameter of the body portion of the axle, so that it may be turned back over the same, substantially as described.

In testimony whereof we have hereunto set 50 our hands in the presence of two subscribing witnesses.

NAPOLEON TEBO.
THEODORE B. FRENCH.
